DESIGN FOR A SMOCK OR SIMILAR ARTICLE

Clementine M. Eich, St. Cloud, Minn.

Application December 12, 1941, Serial No. 104,602

Term of patent 3½ years

To all whom it may concern:

Be it known that I, Clementine M. Eich, a citizen of the United States of America, residing at St. Cloud, in the county of Stearns and State of Minnesota, have invented a new, original, and ornamental Design for a Smock or Similar Article, of which the following is a specification, reference being had to the accompanying drawing, forming part thereof.

I claim:

The ornamental design for a smock or similar article, as shown.

CLEMENTINE M. EICH.
